LIGHTING UNIT

Filed Nov. 22, 1928

Inventor:
Cromwell A. B. Halvorson,
by *Charles E. Tulla*
His Attorney.

UNITED STATES PATENT OFFICE

CROMWELL A. B. HALVORSON, OF LYNN, MASSACHUSETTS, ASSIGNOR TO GENERAL ELECTRIC COMPANY, A CORPORATION OF NEW YORK

LIGHTING UNIT

Application filed November 22, 1928. Serial No. 321,196.

My invention relates to lighting units. More particularly it relates to units of a type especially adapted for use in connection with street lighting.

It is very often the case that residents along a street where such units are located near the buildings object to the direct rays of light from the units. In certain instances shields have been interposed between the globe and the light source in the unit in order to intercept or tone down the light. In such cases marked shadows are formed on the globe which show very markedly from the side and which for that reason detract from the appearance of the unit. It is an object of my invention to overcome the above objection by providing a lighting unit with a form of globe which will overcome the above objection. For example, it is an object of the invention to provide a lighting unit with a globe made in angular form and with the shield so located with respect to the light source that the shadow produced by the shield falls altogether on one of the sides between the ridges formed where the sides come together, with the result that the globe when viewed from the side shows a shadow of little or no depth or is so obscured that the outline of the unit is not marred. The invention also contemplates the use of means for supporting the shield in position with its edges in such alignment with the ridges so as to insure that the shadow shall fall in its proper place.

However, the features of the invention will be better understood from the following specifications and claims, reference being had to the accompanying drawings in which Fig. 1 is a view in elevation and partly in section of a lighting unit comprising features of the invention. Fig. 2 shows the globe of the unit in section and in elevation with the top removed and separated from the base. In this figure the shield is shown in position. Fig. 3 shows the globe in section taken on line 3-3, Fig. 2. This figure shows the globe clearly to be angular and shows the formation of special ridges where the sides come together. Fig. 4 shows similar view of a globe in which the sides are

less curved than in the form of globe shown in Fig. 3. Fig. 5 is a sectional top view of a plain rectangular globe with the shield interposed between the light source and one of the sides. Fig. 6 is a top sectional view of plain triangular globe with the shield interposed between the light source and one of the sides.

Referring more in detail to the drawings, it will be seen that the unit comprises a base 2, a globe 3 and a canopy 4. Resting on the top of the globe 3 is a frame in the form of a ring 6. This ring is provided with a number of angle pieces 7, equally spaced, only two of which are shown, which are suitably secured to the ring 6. For example, they may be spot welded to the ring. Each of these angle pieces is provided with a top section which extends over the top of the ring and which rests on the top rim of the globe. Each of these pieces is furthermore provided with a screw 10 which serves to clamp the frame to the top of the globe. The frame is provided with a central arched member 13, see Fig. 2, which is hinged on the left of the ring 6. On the right the member 13 may be latched to the ring 6 in any suitable manner. For example, as indicated, the end of the member 13 is bent at right angles and a slot is provided in the ring through which the end may enter and latch with the ring. At the top of the element 13 there is provided a threaded pin 14 which receives the threaded pinnacle member 15. It will be seen that the canopy 4 is clamped in position between the globe 3 and the element 15.

Secured to the base 2 is a lamp socket 16 for receiving the electric lamp 17. Interposed between the lamp 17 and the globe 3 is a shield 18. This shield, as shown in Figs. 1 and 2 hangs from the ring 6. Preferably the inner surface of the shield, that is, the surface next to the electric light, is in the form of a reflecting surface. The globe in Figs. 1, 2, 3, and 4 is provided with a number of ribs 19, 20, 21, and 22. As indicated in Fig. 3, the shield 18 will form a shadow that will fall on the globe between the lines 23 and 24 when the light is turned on.

Therefore the edges of the shadow will fall within the region marked by the ribs 19 and 20, with the result that the disagreeable effect caused by the edge of the shadow is avoided due to the fact that the rib breaks the continuity of the surface of the globe and operates to hide the sharp demarkation of the shadow.

In Fig. 3 the shield is shown on the narrower side of the globe, but in certain instances it may be desirable to place the shield on the broader side of the globe, that is, on the upper side, Fig. 3, in which case a larger shield would be used.

In Fig. 4 the type of globe shown has sides with less curvature than the sides shown in Fig. 3. As indicated in this figure, the curvature is such that it does not rise above the line 25—25 which barely grazes the ridges 26 and 27 formed respectively by the sides 28 and 29, and 28 and 30. Inasmuch as the curvature of the sides is as indicated the shadow cast by the shield 32 on the side 31 will not be visible or will be negligibly visible. With the form of globe shown in Figs. 5 and 6 accentuated ridges, such as the ridges 19, 20, 21 and 22 in Fig. 3, are not necessary because the shadow, for example, which falls from the shields 33 and 34 on the sides 35 and 36 respectively, when viewed from one side, presents no depth and consequently the outline of the globe is not affected by the shadow.

By my invention I provide an improved lighting unit in which a shield may be used and in which the globe is designed with ribs or ridges between which the shadow cast by the shield falls to prevent the shadow from interfering with or affecting unfavorably the outline of the unit.

It will be understood that while I have elected to illustrate my invention in connection with the specific form of apparatus shown in the drawings, I do not care to be limited to this particular form of apparatus, inasmuch as I contemplate variation and modifications suggested by the disclosure which do not depart from the spirit of the invention nor from the scope of the claims contained herein.

What I claim as new and desire to secure by Letters Patent of the United States, is:

1. In combination in a lighting unit, a globe for enclosing a source of light, said globe having sides which extend at substantial angles to each other, a shield for the light located between the central axis and a side of the globe, and means for supporting the shield in place in such relation that the edges of the shadow formed by the shield when the light is turned on fall along the edges of one of said sides.

2. In combination, in a lighting unit, a globe for enclosing a source of light, said globe having side walls which extend at substantial angles to each other, a shield for the

light located between the central axis and a side of the globe, and formations on the globe corresponding to the edges of the shadow cast by the shield on the globe when the light is turned on, said formations operating to frame the shadow.

3. In a lighting unit, a globe adapted to enclose a light source and having sides located at substantial angles with respect to each other, and a light shield interposed between one of the sides of the globe and the longitudinal axis thereof in position to cast all its shadow on said side when the light in the globe is turned on.

4. In a lighting unit, a globe adapted to enclose a light source, said globe having not less than three curved sides that meet to form ridges along planes passing through the longitudinal axis of the globe, and a light shield located in the globe and interposed between one of said sides and the longitudinal axis of the globe whereby when a light source is placed in said globe along said axis the shield casts all its shadow on one of said sides.

5. In a lighting unit, a globe having not less than three curved sides located at an angle each with respect to the other about a longitudinal axis of the globe, the location of the sides with respect to each other being such that a plane transverse the axis of the unit forms a broken curve along the line of intersection of the transverse plane with the surfaces of said sides, and a light shield interposed within the globe between one of said sides and the longitudinal axis of the globe in such position that when a lighting source is placed in the globe along said axis the shield casts all its shadow on one of said sides.

6. The combination with a globe comprising a plurality of side walls that merge into each other at their edges to form angular corners, of a shield in the globe located in spaced relation to a side of the globe and of a size such that the shadow cast by it falls along the angular corners of the edges of such side.

In witness whereof, I have hereunto set my hand this 19th day of November, 1928.

CROMWELL A. B. HALVORSON.
